UNITED STATES PATENT OFFICE.

ALBERT TAYLOR RHODES, OF WORCESTER, MASSACHUSETTS.

PAVEMENT.

1,348,959.

Specification of Letters Patent. Patented Aug. 10, 1920.

Application filed April 4, 1919. Serial No. 287,474.

To all whom it may concern:

Be it known that I, ALBERT T. RHODES, a citizen of the United States, residing at Worcester, in the county of Worcester and 5 Commonwealth of Massachusetts, have invented a new and useful Improvement in Pavement, of which the following, together with the accompanying drawings, is a specification.

10 My present invention relates to a pavement in which blocks of granite, brick, or other material, is exposed to the wearing surface of the pavement, and my invention has for its object to provide a wearing surface 15 possessing a uniform resistance to the wear of the traffic passing over it. The method of laying the pavement in accordance with my invention is hereinafter described and illustrated in the accompanying 20 drawings, in which—

Figure 1 denotes a transverse sectional view of a street pavement having the wearing surface of the pavement composed in part of rectangular granite blocks and belonging to that class of pavement commonly 25 known as block pavement.

Fig. 2 is a transverse sectional view of a paved street, in which a portion of the wearing surface is composed of pieces of broken 30 rock of irregular outline.

Similar reference characters refer to similar parts in both figures.

In laying my improved pavement, I give the proper shape and crown to the roadbed 35 *a* upon which I lay a foundation *b*, preferably composed of broken stone, sand and hydraulic cement, mixed in any given proportions as determined by the judgment of the builder. Upon this foundation, as illus- 40 trated in Fig. 1, I place a series of paving stones or blocks *c* suitably spaced apart, and in the joints between the blocks *c* I place a joint filler *d* filling the space from the foundation *b* to about one-half or two-thirds the

45 height of the blocks *c*. This filler may be composed of sand and hydraulic cement to which finely broken stone may be added. As thus far described, the method of laying the block pavement illustrated in Fig. 1 corresponds to the method now generally practised in laying pavement of this class. 50

My improvements consists in providing a uniform wearing surface for the pavement,

and to this end I make a test of the wearing surface of the blocks *c*, and when this has 55 been determined, I provide a composition for filling the upper portion of the joints between the blocks *c* having the same wearing resistance as the blocks, as shown at *e*, Fig. 1. The filler *e* is formed by the addition to hydraulic cement of some hardening material, either as a substitute for or in addition to sand, such for example as carborundum, corundum, alundum, or similar material, thereby forming the upper part of 60 the filler *e* of the same resistance to wear as the blocks *c*. When a pavement is thus laid, the joints between the blocks will offer the same resistance to wear as the blocks themselves, thereby maintaining a smooth upper 65 surface when subjected to the abrasive action of traffic. The entire joint between the blocks *c* may be treated as above described if desired, but the concrete filling *d* serves the purpose of supporting the hard 70 filler *e* and is less expensive to compound. 75

It is now a common practice to determine the resistance to wear of different grades of paving blocks, but so far as I am aware it is broadly new to provide a joint filler having approximately the same wearing surface as the blocks themselves. 80

In Fig. 2 I have shown a modification in which the blocks *c'*, of irregular shape, are embedded in a plastic material *d'*, composed 85 preferably of hydraulic cement and carborundum, corundum or alundum, or similar hardening material, in sufficient proportions to render said plastic material when set to have the same wearing resistance as the 90 blocks *c'*. The blocks *c'* may be mixed with the plastic material *d'* before the latter is applied, or they may be forced into it by pressure. 95

The joint filler *e*, as shown in Fig. 1, or the plastic surface coating *d'*, as shown in Fig. 2, should present the same resistance to wear as the paving blocks *c* or as the irregular pieces *c'*, and this wearing resistance may be produced by the mixture of 100 any hard material, such as those I have described, with either hydraulic cement, bitumen, mastic, pitch, or other plastic material now employed in road paving. The object of my invention is secured by filling 105 the interstices between the blocks *c* or *c'*

with a plastic material having substantially the same wearing surface as the blocks embedded therein.

I claim,

- 5 1. A pavement consisting of a suitable foundation, a series of paving blocks supported thereon and spaced apart, and a joint filler in the interstices containing carborundum or a like material to increase the 10 wearing surface of the joint filler.
2. A pavement consisting of a suitable foundation for a series of paving blocks, paving blocks supported by said foundation and spaced apart, a joint filler of plastic 15 material for the lower portion of the interstices between said block, and a joint filler for the upper portion of the interstices be-

tween said blocks flush with the upper surface of the block and containing carborundum or a like material to increase the hardness of said upper portion. 20

3. A pavement consisting of a plastic foundation of broken stone, sand and hydraulic cement, a series of granite paving blocks supported thereon and spaced apart, a joint filler in the interstices having its 25 upper or wearing surface containing carborundum or like material to render the wearing surface of the joint filler of equal resistance to wear as the paving blocks.

ALBERT TAYLOR RHODES.
